UNITED STATES PATENT OFFICE

157,456

UNDERCARPET PADDING

Bernard F. Wills, Brooklyn, N. Y., assignor to
United States Rubber Company, New York,
N. Y., a corporation of New Jersey

Application August 21, 1948, Serial No. 148,230

Term of patent 14 years

(Cl. D92—4)

To all whom it may concern:

Be it known that I, Bernard F. Wills, a citizen of the United States, residing at Brooklyn, in the county of Kings and State of New York, have invented a new, original, and ornamental Design for Undercarpet Padding, of which the following is a specification, reference being had to the accompanying drawing, forming part thereof.

Fig. 1 is a plan view of a portion of undercarpet padding showing my new design;

Fig. 2 is an edge view looking at the lower edge of the section of Fig. 1; and

Fig. 3 is an edge view looking at the right hand edge of the section of Fig. 1.

I claim:

The ornamental design for undercarpet padding, as shown.

BERNARD F. WILLS.
